UNITED STATES PATENT OFFICE.

WILLIAM C. DICKMEYER, OF FORT WAYNE, INDIANA, ASSIGNOR TO PERFECTION BISCUIT COMPANY, OF FORT WAYNE, INDIANA, A CORPORATION OF INDIANA.

DESIGN FOR A CRACKER-CAN.

52,562.

Specification for Design.

Patented Oct. 15, 1918.

Application filed June 28, 1915. Serial No. 36,874. Term of patent 14 years.

To all whom it may concern:

Be it known that I, WILLIAM C. DICKMEYER, a citizen of the United States, residing at Fort Wayne, in the county of Allen and State of Indiana, have invented a new, original, and ornamental Design for Cracker-Cans, of which the following is a specification, reference being had to the accompanying drawing, forming a part hereof.

Figure 1 is a perspective view of a cracker can embodying my invention;

Fig. 2 is a section taken horizontally

through the upper label receiving panel; and

Fig. 3 is a similar section taken through the window through the lower label receiving panel.

I claim:

The ornamental design for a cracker can, as shown.

WILLIAM C. DICKMEYER.
